(57) **CLAIM**

The ornamental design for a temperature probe as shown and described.

DESCRIPTION

FIG. 1 is a top right perspective view of the temperature probe of our design;

FIG. 2 is a top left perspective view of the temperature probe of FIG. 1;

FIG. 3 is a top plan view of the temperature probe of FIG. 1;

FIG. 4 is a left side elevation of the temperature probe of FIG. 1;

FIG. 5 is a front elevation of the temperature probe of FIG. 1;

FIG. 6 is a bottom plan view of the temperature probe of FIG. 1;

FIG. 7 is a right side elevation of the temperature probe of FIG. 1;

FIG. 8 is a rear elevation of the temperature probe of FIG. 1; and,

FIG. 9 is a top right perspective view of the temperature probe of FIG. 1 shown in an alternate position.

The broken lines in FIG. 6 are included for the purpose of illustrating portions of the temperature probe and form no part of the claimed design.

The break lines in FIG. 9 indicate that the appearance of any portion of the temperature probe between the break lines forms no part of the claimed design.
